CLAIM

The ornamental design for a curved wheel leveler and chock set, as shown and described.

DESCRIPTION

FIG. 1 is a left, front perspective view of a curved wheel leveler and chock set showing our new design;

FIG. 2 is a right, back perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the curved wheel leveler and chock set that form no part of the claimed design.

1 Claim, 7 Drawing Sheets
